UNITED STATES PATENT OFFICE.

IONE MILLER, OF BRADFORD, PENNSYLVANIA.

DETACHABLE BUTTON.

No. 820,588.

Specification of Letters Patent.

Patented May 15, 1906.

Original application filed May 9, 1905, Serial No. 259,505. Divided and this application filed September 1, 1905, Serial No. 276,745.

To all whom it may concern:

Be it known that I, IONE MILLER, a citizen of the United States, residing at Bradford, in the county of McKean and State of Pennsylvania, have invented certain new and useful Improvements in Detachable Buttons; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate the invention, and said invention is fully disclosed in the following description and claim s.

This invention is a division of my application for Letters Patent of the United States, filed May 9, 1905, Serial No. 259,505.

Referring to the said drawings, Figure 1 represents one of my improved detachable buttons, showing it used for the purpose of attaching a nether garment to a child's shirt-waist, portions only of said garments being shown. Fig. 2 represents one of said buttons attached to a loop of tape on a garment such as a child's waist. Fig. 3 represents one of said buttons detached. Fig. 4 represents a slight modification of my improved button.

This invention consists of an improved detachable button which is adapted particularly for use with washable garments where it is desirable to remove the buttons before laundering, such as children's shirtwaists, but which may be employed for any purpose for which they may be found convenient or desirable.

In its simplest form it consists of a button proper or head, to which is attached a flexible loop of tape, cord, or other flexible material of sufficient size and length to be passed over the head of the button after inserting the loop through a tape, buttonhole, strap, or other device secured to a garment or other article.

In Fig. 3 I have illustrated my preferred form of the device, which consists of the head or button proper, D, in the form of a disk, of bone, pearl, rubber, or other suitable material, provided with two holes d d, through which is passed an endless attaching band or loop d'. I prefer to form this loop of soft woven cord or tape and to attach thereto midway between the button D and the outer end of the loop d' a cross-piece d², of fabric, such as a piece of tape folded upon itself and stitched to the loop d'. The tape of the

cross-piece is preferably folded upon the loop and stitched all around its edges and across its center, as shown, thereby securing the tape to the loop, and the two ends of the 60 piece of cord or tape forming the loop d' may be brought between or under the cross-piece d² before stitching on the cross-piece, thus simultaneously securing the ends of the loop.

In Fig. 4 I have shown a simpler form of 65 the detachable button, consisting of the disk or head D' and a simple endless loop d⁴, passed through the two holes d³ d³ in the disk. In some instances it is found desirable to form the attaching-loop of the buttons of elastic material, so that the loop may yield slightly when subjected to considerable strain to avoid breaking or detaching the loop from the head or from the garment with which it is used. To attach the but- 75 ton, it is only necessary to pass the attaching-loop under a strap—such as the strap a, illustrated in Fig. 2—which is secured to a garment A, illustrated fragmentarily, (such as a child's shirt-waist,) or through a loop, 80 eye, buttonhole, or other aperture affording a hold for the loop, and then to pass the head of the button through the end of the loop, as shown in Fig. 2. Where the cross-piece d² is employed, it will prevent the loop from 85 drawing up tightly, and thus hold the head or button proper closer to the point of attachment to the garment. The use of this cross-piece also renders it easier to remove the buttons when it is desired to do so. 90

Another method of using the detachable button is illustrated in Fig. 1, in which A' represents a portion of a child's shirt-waist provided with a strap a' near the waist-line, from which it is desired to support the nether 95 garment, a portion of which is illustrated at B and which is provided with a strap b. In this case the loop d⁴ of the button is passed beneath straps b and a', and the loop is then passed over the head of the button, thus securing the two garments together. 100

What I claim, and desire to secure by Letters Patent, is—

1. A detachable button consisting of a head or disk provided with an attaching-loop 105 of flexible material, for connection with a loop-engaging device on a garment, said loop being of sufficient length to pass over the head or disk and extend beyond the periphery thereof, for detachably securing the button to a garment, substantially as described.
2. A detachable button consisting of a

- disk or head provided with a pair of apertures and an endless attaching-loop of flexible material extending loosely through both of said apertures and of sufficient length to pass over the head or disk and extend beyond the periphery thereof for detachably securing said button to a garment, substantially as described.
3. A detachable button for garments comprising a head, a loop of flexible material secured thereto, and a cross-piece secured to said loop between the head and the opposite end of the loop, substantially as described.
4. A detachable button for garments comprising a head or disk having two apertures therein, a loop of flexible material passing through said apertures, and having its ends meeting at a point between the head and the opposite end of the loop, and a cross-piece secured to said loop at the meeting-point of the

end of the same, and uniting said meeting ends, substantially as described.

5. A detachable button for garments comprising a head or disk having two apertures therein, a loop of flexible material passing through said apertures, and having its ends meeting at a point between the head and the opposite end of the loop, and a cross-piece of fabric placed across said loop at the point where the ends thereof meet, and stitched to said loop, thus securing the cross-piece to the loop and also uniting the ends of the loop, substantially as described.

In testimony whereof I affix my signature in the presence of two witnesses.

IONE MILLER.
